UNITED STATES PATENT OFFICE

161,912

PORTABLE WELDING APPARATUS

Joseph A. Fotie, Kansas City, Mo., assignor to Rex Welder & Engineering Co., Kansas City, Mo., a corporation of Missouri

Application July 20, 1950, Serial No. 11,271

Term of patent 7 years

(Cl. D26—5)

To all whom it may concern:

Be it known that I, Joseph A. Fotie, a citizen of the United States, residing at 6139 Morning-side Drive, Kansas City, in the county of Jackson and State of Missouri, have invented a new, original, and ornamental Design for a Portable Welding Apparatus, of which the following is a specification, reference being had to the accompanying drawing, forming a part thereof, wherein:

Fig. 1 is a perspective view of a portable welding apparatus, showing my new design.

Fig. 2 is a rear elevational view thereof; and Fig. 3 is a top plan view thereof.

I claim:

The ornamental design for a portable welding apparatus, as shown.

JOSEPH A. FOTIE.
